COIN CHUTE

Vernon H. Anderson, Salt Lake City, Utah

Application April 8, 1946, Serial No. 660,546

4 Claims. (Cl. 194—103)

1

This invention relates in general to a coin chute for automatically ejecting coins, or slugs, checks, and the like, which are underweight or overweight, by discharging them laterally from the chute.

An important object of the invention is to provide automatic selective means for laterally discharging coins from a chute when they are underweight by engaging them with a projection which ejects the coin through an opening at one side of the chute.

A further object of the invention is to provide means for selectively discharging a coin which is overweight from a laterally apertured coin chute by providing a variable coin supporting track in the chute so far depressed by an overweight coin that it will be ejected laterally from the chute.

Still a further object of the invention is to provide an automatic coin ejecting chute in which a pivoted leaf forming a coin supporting track is delicately supported upon a tensioned spring whose tension may be adjusted so that if the coin is overweight or underweight, the leaf will be improperly depressed, and the defective coin will be ejected from an opening at one side of the chute.

Still a further object of the invention is to provide a coin ejecting chute having a testing chamber which is inclined downwardly and laterally with an opening at the relatively under side of the chute and having an adjustable spring leaf forming a track therein which must be depressed the correct distance or the coin will be discharged from the opening.

Still a further object of the invention is to provide a selective coin ejecting chute which has a passage inclined downwardly and transversely with a spring leaf forming a track in the passage, and a projection above the leaf to deflect underweight coins through an opening in one side of the chute, but delivering coins of the required weight through the passage against a chime or bell which will give a signal that the coin is of the required weight.

Other objects of the invention will appear in the specification and will be apparent from the accompanying drawings in which.

Fig. 1 is a side elevation of a coin ejecting chute in accordance with this invention, the spring track therein being in its normal unstressed position;

Fig. 2 is a view in transverse section, taken on line 2—2 of Fig. 1;

Fig. 3 is a central longitudinal section showing

2

the spring track in position for ejecting a light-weight coin;

Fig. 4 is a detail in section taken on line 4—4 of Fig. 1;

Fig. 5 which is a view similar to Fig. 3, shows the position of the track for ejection of an overweight coin;

Fig. 6 is a central longitudinal sectional view showing a modification of the pivoted track and its adjusting means; and

Fig. 7, which is a view similar to Figs. 3 and 5, shows the position of the track for movement thereover of a coin of proper weight.

This coin ejecting chute is particularly described as a selective device for use with coin telephones although it may have a more general use wherever applicable. Each coin chute is designed and intended to receive coins of a certain size and weight, within predetermined limits, such as a nickel, a dime, or a quarter. This invention is to automatically discharge definitely underweight or overweight coins from the particular coin chute, and also to discharge other checks, slugs, and the like, which are underweight or overweight. Although the invention is therefore described as a coin ejecting chute, it is to be understood that this term also includes slugs, checks, or other devices which may be no larger than the proper size for insertion in the chute but are definitely underweight or overweight, or are not proper coins to be received therein.

Although coins of different weights may pass through the downwardly inclined chute at different speeds, the present invention does not depend upon such differences in speed but rather on the lateral inclination of the chute, the lateral discharge opening, the yieldable coin track, and the cam projection for ejecting light weight coins.

Referring now more particularly to the drawings, a prepayment type of telephone coin chute is shown, comprising a base plate B having an entrance passage 10 of a size depending upon the denomination of the coin to be inserted. This entrance passage which leads downwardly from the top, continues laterally past a deflector 11 through a testing chamber 12 which is downwardly inclined to its exit end 13. To complete the chute, a cover plate 14 may be secured to the base plate thereby entirely enclosing the passage and the testing chamber, the two plates being secured together at their edges by any suitable fastening means such as screws or bolts 15 and nuts 16. The base plate is designed for fixed attachment to a mounting plate (not shown) in

any appropriate way, with the testing chamber downwardly inclined away from the deflector 11 and laterally inclined away from the vertical.

At the relatively under or lower side of the inclined coin chute, and extending through the wall of the base plate is a discharge opening 21 defined by a rounded extremity 22 at one end, two straight intermediate portions 23 spaced apart slightly less than the proper coin to be discharged through the chute, and an upwardly extending recess 24 which both exposes and merges with a cam in the form of a beveled projection 25, near the exit end of the testing chamber. The lower or exit end 13 of the coin chute comprises an abutment 26 at the bottom of the base plate B.

Within the coin chute at the bottom of the testing chamber 12 and mounted in the base plate B is a yieldable coin supporting track preferably comprising a spring leaf 30 of thin metal or other suitable material having a supporting eye 31 at one end for mounting it upon a pivot 32 extending from the base plate B. The other end of the leaf track is mounted for a limited free movement by means of a hooked extremity 33 extending downwardly and embracing a fixed pivot or projection 34 extending inwardly from the plate B and limiting the upward and downward movement of this end of the track. Below the limiting projection 34 and the hooked extremity 33 is a recess 35 to receive the hooked end and allow it to move downwardly when the track is depressed.

To hold the track resiliently upward, a flat spring 36 is mounted at one end in a boss 37 adjacent the recess 35 by inserting one end of the spring 36 into a receiving slit 38 in the boss, the other end of the spring bearing upon the yieldable track 30 at the under side adjacent its pivot 32 so that the spring 36 tends to press the track 30 to its uppermost position. To vary the tension of the spring 36, an adjusting screw 39 may be inserted through the bottom of the base plate B adjacent the projection 37 so that the inner end of the screw engages the leaf spring 36, and by adjusting the screw, the tension of the spring, and consequently the upward pressure of the track 30, may be varied and set as desired.

A modification of the spring structure is shown in Fig. 6 in which a resilient leaf 40 forming the bottom track for the chute has a hooked extremity 41 at the free end engaged by the projection 34. The mounting of the leaf at the other end comprises a bracket 42 supported by a pivot 43. To press the track 40 upwardly, a compression spring 44 is mounted in a tubular sleeve 45, below and adjacent the bracket 42 with an adjusting screw 46 threaded into the end of the sleeve 45 and having a block 47 interposed between the end of the screw and the adjacent end of the spring 44 so that as the screw 46 is adjusted, the spring 44 is forced more or less tightly against the bracket 42, thus varying the tension applied to the under side of the track 40. A lock nut 48 engages the screw 46 and the end of the sleeve 45 for locking the screw and the spring 44 in any adjusted position.

In each of these constructions, the vertical width of the opening is slightly less than the diameter of the intended coin. The resilient leaf which constitutes the bottom of the coin track will be depressed in an amount depending upon the weight of the coin which traverses the chute. Three positions of a proper coin a, a lightweight coin b, and an overweight coin c are illustrated

in Figs. 7, 3 and 5 respectively. A lightweight coin b will depress the yieldable leaf 30 only slightly so that its path of movement through the testing chamber is relatively high (see Fig. 3); as the coin moves down the chute, it is engaged by the cam projection 25 which deflects the coin from the lower end of the chute as represented in Fig. 4. An overweight coin c depresses the resilient leaf 30 (or 40) a greater distance so that 10 the path of coin travel through the testing chamber is relatively low (see Fig. 5); the uppermost edge of a heavy coin will clear the top edge of the opening 21, and since the coin chute is laterally inclined, the coin is free to fall out of 15 the lateral opening 21 and will do so before it reaches the cam projection 25. A coin a of proper size and weight will depress the resilient leaf 30 to only a minor extent such that the path of travel for the coin will be intermediate, allowing the coin to be guided at its top by the uppermost edge and straight portion 23 of the opening, while avoiding engagement by the cam projector 25 within the testing chamber (see Fig. 7). The upper portion of the end wall 24 of the discharge opening 21 may be formed with an inner beveled edge 51 (see Fig. 4) which assists in engaging and guiding a coin of proper size and weight within and through the chute for discharge through the end exit 13.

30 The inner edge 52 of the opening 21 opposite the beveled surface 51 may also be beveled, as shown more clearly in Fig. 4, to assist the projection 25 in camming a lightweight coin outwardly through the discharge opening. This constitutes a means of very delicate adjustment when operated in conjunction with a laterally inclined coin chute. Since the lateral inclination alone is sufficient to eject some coins, and the operation of the resilient track in conjunction 40 with the beveled projection ejects other coins, it is possible to make a very sensitive determination of the proper coins which will traverse the chute.

45 In one sense the resilient track is a lever of the third class, its pivoted end being the fulcrum; the effort which is resiliently applied is the leaf spring 36, or the compression spring 44, as the case may be; this effort is applied at a point that is relatively close to the fulcrum end of the lever 50 30 or 40 (as the case may be) forming the track along which coins are successively rolled during their passage through the testing chamber; and the tension exerted by the effort against the under side of the track lever may be adjusted very 55 closely so that the yielding support for the resistance or free end of the lever can be controlled with extreme accuracy. It is largely this delicately balanced mounting for the coin track that is responsible for the dependable ejection of off-weight coins passing therewith while moving through the testing chamber.

60 While a preferred construction and arrangement of parts has been described, it should be regarded as an exemplification and not a limitation of the invention, as various changes may be made in the construction, combination and arrangement of the parts without departing from the spirit and scope of the invention.

I claim:

70 1. A coin ejector chute inclined downwardly and having means forming a laterally inclined coin passage with an opening along the relatively under side, means forming a resilient track for coins in the passage along the opening depressed 75 relative to the weight of a coin, a projection at

one side of the top of the passage to engage an underweight coin on the track and deflect it from the opening, and an overweight coin depressing the track to bring the top of the coin below the top of the opening to discharge the coin by gravity from the inclined passage.

2. A coin ejector chute inclined downwardly and having means forming a laterally inclined coin passage with an opening along the relatively under side, means forming a resilient track for coins in the passage along the opening depressed relative to the weight of a coin, the track being sufficiently depressed by an overweight coin to discharge it through the opening from the inclined passage by gravity, means to engage an underweight coin on the track for ejecting it from the passage through the opening, and the track being sufficiently depressed by a coin of proper weight to avoid said engaging means and to pass through the passage without deflection from the opening.

3. A coin ejector chute inclined downwardly and having means forming a laterally inclined coin passage with an opening along the relatively under side, means along the opening forming a resilient track for coins in the passage depressed relative to the weight of a coin, means including a projection for engaging light weight coins and discharging same from the opening through which also overweight coins tend by gravity to be discharged, and the track positioning a coin of proper weight to engage the inside of the chute above and below the opening and free from said projection to pass clearly through the chute.

4. A coin ejector chute comprising means forming a coin passage inclined downwardly and laterally from the vertical with an opening extending lengthwise of the passage along the relatively underside thereof, the width of the opening vertically being slightly less than the diameter of the intended coin except at the downward end where it is enlarged upwardly, a lateral projection forming a coin ejection cam internally of the passage opposite the upward enlargement of the opening, and a bottom track for the coin passage yieldable downwardly in response to the weight of a passing coin whereby the latter, if underweight, is permitted to advance through a relatively high path to encounter the lateral projection and be cammed thereby for ejection laterally through the opening, and if overweight, is caused to advance through a relatively low path wherein it clears the top edge of the lateral opening for gravity discharge therethrough.
